TUNING MECHANISM

Ludwig J. Fichter, Dayton, Ohio, and Bertram A. Schwarz, Kokomo, Ind., assignors to General Motors Corporation, Detroit, Mich., a corporation of Delaware

Application October 21, 1942, Serial No. 462,832

10 Claims. (Cl. 172—239)

This invention relates to indexing means and more specifically to means to index to definite predetermined angular positions a rotatable member by the closure of certain switch means. Present day constructions frequently require the use of indexing means for various purposes such as machine tools, radio receivers, and other apparatus. In these constructions it is necessary to provide automatic means to bring movable members to set positions upon the simple actuation of a reciprocating rod or switch member. This is particularly true in the application of so-called push button or automatic tuners on radio receivers, although this is only one specialized application of our present invention.

It is therefore an object of our invention to provide indexing means for bringing a mechanical part to a predetermined position which may be operated by a minimum of movement of translationally movable push buttons.

It is a further object of our invention to provide an indexing means capable of moving to a plurality of different positions and controllable by a plurality of different push buttons.

It is a still further object of our invention to provide indexing means automatically operable to accurately adjust desired parts.

It is a still further object of our invention to provide indexing means capable of bringing a rotatable means to different angular positions controlled by a plurality of push button switches.

With these and other objects in view which will become apparent as the specification proceeds, the embodiments of our invention will be best understood by reference to the following specification and claims, and the illustrations in the accompanying drawing, in which:

Figure 1 is a schematic showing of a system embodying our invention; and,

Figure 2 is a schematic showing of a modification of a portion thereof.

There are of course a number of different ways in which members can be automatically moved to predetermined positions and particularly means to tune resonant circuits in a radio receiver so that the same will be receptive to different transmitting stations. One of these indexing means of the so-called "drum" type is shown in a pending application Serial No. 394,071 filed May 19, 1941, in the names of Fichter and Kaegi and entitled "Tuning mechanism" in which a rotating drum carries a series of radially projecting members to do the actual tuning. Since the drum per se forms no part of the present invention, it is only shown as a circular drum and it will not be necessary to describe the same here in detail, but let it suffice to say that the rotating drum carries the necessary final indexing means and the present invention is concerned with means for rotating the drum.

Referring now more specifically to Figure 1, there is shown therein a rotating drum 2 which, as just mentioned, carries the adjustable indexing means at different angular positions. On the 5 end of this drum there is mounted a circular conductive ring 4 and also a ratchet gear 6, the latter being secured to the shaft 8 and rotating with the drum about this axis. Fixedly mounted adjacent the periphery of the drum and spaced at arcuate distances from each other are a series of conductive brush members 10, 12, 14, 16, 18 and 20 adapted to contact the ring 4. These are supported by the surrounding frame. They extend to the conductive ring 4 and at substantially 10 all points conduct current to this ring. Each of these conductive brush members is connected by lines 22, 24, 26, 28, 30 and 32 to a series of spring-biased contacts 34, 36, 38, 40, 42 and 44, respectively. Cooperating with each of the last-mentioned 15 spring contacts are a series of stationary contacts 46, 48, 50, 52, 54 and 56, all of which are connected to line 58 and thus to one terminal of a battery 60 or other source of power.

These various switch assemblies are mounted 20 adjacent a series of reciprocating plungers 62 which are actuated by a series of push buttons 64 which extend through the front panel of the supporting casing. Each of these push buttons is provided with an enlarged head and a smaller 25 throat which latter extends through a plurality of openings 66 in a plate 65 extending the full length of the push button assembly. One end of this plate carries a contact 68 which moves therewith and cooperates with fixed contact 70 which is connected by line 72 to the speaker of the receiver. Thus when any push button is depressed, the plate 65 will be moved inwardly to close the switch 68—70 and short out the speaker so that no sound may issue therefrom during the 30 tuning operation.

The throat of each push button 64 also carries a small pin 74 which is adapted to be forced into a V groove formed between two adjacent sections of slide members 76 which extend the full width 35 of the tuning unit and are kept in alignment by two stationary blocks 78 at each end thereof. There is just enough clearance between all of these slideable units 76 to allow one pin 74 to proceed to its full inward position and when in this 40 position, as will be evident from the drawing, none of the other pins 74 can be pushed inwardly to their fullest degree as the notch at this point will be closed and prevent such action. Thus only one push button at a time can be forced to its 45 full position, the slides providing lock-out means.

Supported on the central section of each of the 50 reciprocating pins 62 is a magnetic sleeve 80 which when the reciprocating assembly is in its outer position is off center between the two arms 82 and 84 of an electromagnet which is provided 55

with energy from an energizing coil 86. When, however, the reciprocating push button assembly has been forced inwardly, the magnetic sleeve moves to a position bridging the arms and provides a path of low reluctance for the flux between the arms of the electromagnet and the push button assembly is maintained in this position by the energization of the coil 86, all of the assemblies operating in the same manner and the one being depressed only being maintained in its inward position as long as the coil 86 is energized until the device has reached its tuned or indexed position. The coil 86 is deenergized, as will be explained, and there is sufficient strength provided in each spring 88 supporting the series of movable contacts 34, 36, 38, 40, 42 and 44 to force the contacts apart and the reciprocating push button assembly back out to its deenergized position.

There is also supported adjacent the drum in a stationary manner a brush assembly 90 which engages the conductive ring 4 in all angular positions of rotation of the drum. This brush is connected by line 92 to one terminal of the electromagnet 86, the opposite side of which is grounded. It is also connected to a line 94 which terminates in movable contact member 96 carried by a reciprocating member 98 to cooperate with a stationary contact 100. The latter contact is connected by line 102 to one terminal of an electromagnet 104, the opposite terminal of which is likewise grounded. Reciprocating member 98 is mounted in a stationary part 106 which has a spring-biased pin 108 projecting toward the reciprocating member 98 and cooperating with a small projection 110 to maintain the reciprocating member in either of its extreme positions. The member 98 also has two projecting arms 112 and 114 between which oscillates a lever 116 carried by the reciprocating core 118 of the solenoid 104. Thus as the core 118 moves upward and downward, the lever 116 will contact either projection 112 or 114 to also move the reciprocating member 98 to open and close the switch formed by contacts 96 and 100.

A lever 120 is pivotally connected to the top of the core 118 and is spring-biased upwardly by connection to a coiled spring 122, the opposite end of which is secured to the case. Also pivoted to the upper end of the lever 120 is one end of a lever 124, the opposite end of which is pivotally supported upon the shaft 8. This lever 124 carries a pawl 126 which cooperates with the teeth of the ratchet 8. In the outer surface of the conductive ring 4 is provided a notch 128 which is just large enough to accommodate one end of any one of the brushes 10, 12, 14, 16, 18 and 20 so that at one angular position one of these brushes will not make contact with the ring 4, thus breaking the electrical circuit. Brush 90, however, overlies practically the whole width of this ring and therefore remains in electrical contact at all times therewith.

There are shown in this illustration six points at which the rotating indexing drum may be set and of course there are provided an equal number of push buttons to bring the same to these positions. The number of course is not important as any number may be provided, depending upon the desire of the designer.

In the operation of the device one of the push buttons is initially depressed and let it be assumed that the one shown in Figure 1 is the one selected. This movement closes the switch contacts 34 and 46 and if the drum is in any other position than

that shown, a circuit will be completed to the operating solenoid 104 through the following circuit: battery 68, line 58, contact 46, contact 34, line 22, brush 10, conductive ring 4, brush 90, line 92, line 94, contacts 96 and 100, line 102, solenoid 104 to ground. At the same time of course a circuit is completed through the hold-in solenoid 86 and the push button assembly is then maintained in its illustrated position. The solenoid 104 will then be energized to pull its core downwardly and cause the ratchet to move the drum the distance of one tooth. In so doing the arm 116 will contact the arm 114 to move the reciprocating member 98 down past the spring-biased pin 108 and break the switch 96-100. The coil 104 is then deenergized and the spring 122 will at once withdraw the core 118 and return the ratchet assembly to its upper position. If the brush 10 has not reached the position of the groove 128, the operation will be repeated step by step until it reaches the point shown on the drawing. At this time the circuit will be broken; the solenoid will be deenergized; and the push button 64 will be allowed to return to its outermost position through the force of the associated spring 88. The operation of any of the other push buttons will of course be identical to that just described. As previously mentioned, the depression of any of these push buttons will mute the speaker through the operation of the short circuiting switch 68-70 and mechanically lock out any other button.

Figure 2 shows a modified form of ratchet mechanism and drive in which the rotation of the drum about its axis is slower. In Figure 1 each actuation of the ratchet mechanism rotates the drum approximately 60°. However, if we wish to move the drum more slowly, this may be accomplished by the device as disclosed in Figure 2 in which there is shown, as before, a rotatable drum having a plurality of brush members 10, 12, 14, 16, 18 and 20 which only overlie the edge of the conductive ring 4 which as before has a slot 128 therein to break the circuit upon acquiring a definite index. A large brush 90 is also again provided which is adapted to remain in contact with the conductive ring 4 at all times. The associated system is as shown in Figure 1.

In this instance however there is provided a ratchet 8' which has a small number of teeth and this is adapted to cooperate with a pivoted pawl 130 which is carried on the end of a lever 132 which is spring-biased upwardly by a spring 134. The lever 132 is pivoted to a yoke member 136 which carries an operating solenoid 138. The pivoted lever 132 also carries a movable contact point 140 which cooperates with a stationary contactor 142. The circuit from line 92 is through line 144 which is connected to the upper terminal 142. The lower terminal 140 is connected by line 146 to the operating solenoid 138. Thus when the circuit is completed through any one of the brush assemblies 10, 12, 14, 16, 18 and 20, through the conductive ring 4 to the brush 90, current will flow to the operating coil 138 through the brush 90, line 92, line 144, contact 142, contact 140, line 146, solenoid 138 to ground.

The energization of the solenoid will attract the pivoted lever 132 which serves as an armature to ratchet the gear 8' one tooth. In moving downwardly, however, the armature 132 brings with it movable switch contact 140 to break the electric circuit to the solenoid 138 which becomes deenergized and the spring 134 pulls the arma-

ture upwardly again to cause the pawl 130 to ratchet to the next tooth. The upper movement again closes the switch 140-142 and the operation is repeated until whichever brush 10, 12, 14, 16, 18 or 20 is connected to the source of power moves into alignment with the slot 128. It is thus evident that we have provided an automatic means for rotating an indexing member to different angular positions controlled by a plurality of different indexing buttons.

We claim:

1. In an indexing system, a rotatable indexing means, ratchet means to rotate the first-named means, a circular conductor mounted on the rotatable means having an indexing notch thereon, a plurality of brushes overlying the conductor means adapted to enter the slot at one point, means connecting the switching means formed by the brushes and circular conductor to the ratchet means to control the same and a plurality of actuatable means connected to the brushes to close the circuits therethrough and bring the indexing means to a predetermined position, dependent upon which of the actuatable means was moved.

2. In an indexing system, a rotatable drum, solenoid-operated ratchet means to rotate the drum, a plurality of stationary brush assemblies mounted adjacent the drum, a circular conductive ring mounted on the drum to cooperate with the brushes, said ring having a cut-away portion whereby a portion of the brushes would not contact the ring at certain points, a source of power and conductors connecting the source of power to the brushes and to the solenoid whereby the drum movement will be controlled by the switches formed of the brushes and the ring.

3. In an indexing system, a rotatable drum, solenoid ratchet means to rotate said drum step by step, a plurality of arcuately spaced brush means mounted adjacent the drum, a conductor ring mounted on the drum to cooperate with the brush means and having a cut-away portion, conducting means connected to the brushes, a source of power connected to a portion of said connecting means and the solenoid connected to the other portion whereby the brushes control the energization of the solenoid means to bring the drum to different angular positions.

4. In an indexing means, a rotatable indexing drum, ratchet solenoid means to rotate the drum, switching means, a portion of which is mounted adjacent the drum and a portion carried by the drum controlling the solenoid ratchet drive and a second series of switching means connected to the first-named switching means to index the drum.

5. In an indexing means, a rotatable indexing drum, ratchet solenoid drive means for the drum, a conducting ring having a slot therein carried by the drum, a plurality of brush assemblies mounted in spaced relation around the periphery of the drum and engaging the ring but capable of moving into the slot at one angular position, a plurality of push button switches, each connected to one of the brushes, and means connecting the ring to the solenoid drive whereby upon the actuation of a push button to close a switch the solenoid will be energized to move the drum until the brush associated therewith lies in the slot of the ring and the circuit is broken.

6. In an indexing means, a rotatable indexing drum, ratchet solenoid drive means for the drum, a conducting ring having a slot therein carried

by the drum, a plurality of brush assemblies mounted in spaced relation around the periphery of the drum and engaging the ring but capable of moving into the slot at one angular position, a plurality of push button switches, each connected to one of the brushes, means connecting the ring to the solenoid drive whereby upon the actuation of a push button to close a switch the solenoid will be energized to move the drum until the brush associated therewith lies in the slot of the ring and the circuit is broken, and means for holding the push button means in their actuated position until the desired index has been obtained.

7. In an indexing means, a rotatable indexing drum, ratchet solenoid drive means for the drum, a conducting ring having a slot therein carried by the drum, a plurality of brush assemblies mounted in spaced relation around the periphery of the drum and engaging the ring but capable of moving into the slot at one angular position, a plurality of push button switches, each connected to one of the brushes, means connecting the ring to the solenoid drive whereby upon the actuation of a push button to close a switch the solenoid will be energized to move the drum until the brush associated therewith lies in the slot of the ring and the circuit is broken, and interlocking means to prevent the closure of more than one push button switch at one time.

8. In an indexing means, a rotatable indexing drum, ratchet solenoid drive means for the drum, a conducting ring having a slot therein carried by the drum, a plurality of brush assemblies mounted in spaced relation around the periphery of the drum and engaging the ring but capable of moving into the slot at one angular position, a plurality of push button switches, each connected to one of the brushes, means connecting the ring to the solenoid drive whereby upon the actuation of a push button to close a switch the solenoid will be energized to move the drum until the brush associated therewith lies in the slot of the ring and the circuit is broken, means for holding the push button means in their actuated position until the desired index has been obtained, and interlocking means to prevent the closure of more than one push button switch at one time.

9. In indexing means, a rotatable indexing member, step-by-step means to rotate the member, solenoid means to move the step-by-step means in one direction, spring means to move it in the opposite direction, switch means operated by the movement of the step-by-step means to alternately energize and deenergize the solenoid means, and switching means actuated by the rotation of the member in series with the first-named switching means to cause the member to stop at the desired index.

10. In indexing means, a rotatable indexing member, step-by-step means to rotate the member, solenoid means to move the step-by-step means in one direction, spring means to move it in the opposite direction, switch means operated by the movement of the step-by-step means to alternately energize and deenergize the solenoid means, switching means actuated by the rotation of the member in series with the first-named switching means to cause the member to stop at the desired index, and a plurality of switches in parallel connected to the switching means actuated by the rotation of the member to individually initiate an energizing circuit.
